[57] **CLAIM**

The ornamental design for a brush attachment for hair dryer and the like, as shown and described.

DESCRIPTION

FIG. 1 is a perspective view of a brush attachment for hair dryer and the like, showing my new design;

FIG. 2 is an end elevational view thereof;

FIG. 3 is an elevational view of the opposite end thereof;

FIG. 4 is a side elevational view thereof;

FIG. 5 is a bottom plan view thereof;

FIG. 6 is a perspective view of the device attached to a hair dryer, which hair dryer is shown in broken lines for illustrative purposes only and forms no part of the claimed design.

The broken line disclosure of a hair dryer is for illustrative purposes only and forms no part of the claimed design.

FIG. 1

FIG. 2

FIG. 3a

FIG. 3c

FIG. 3b

FIG. 3d
